(57) **CLAIM**

The ornamental design for a shoe sole, as shown and described.

DESCRIPTION

FIG. 1 is a lateral side view of a shoe sole;

FIG. 2 is a first perspective view of the shoe sole;

FIG. 3 is a second perspective view of the shoe sole;

FIG. 4 is a lateral side view of a first element of the shoe sole;

FIG. 5 is a first perspective view of the first element of the shoe sole;

FIG. 6 is a second perspective view of the first element of the shoe sole;

FIG. 7 is a top view of a second element of the shoe sole;

FIG. 8 is a lateral side view of the second element of the shoe sole;

FIG. 9 is a first perspective view of the second element of the portion of the shoe sole; and,

FIG. 10 is a second perspective view of the second element of the shoe sole.

A shoe sole is shown in FIGS. 1-10. The broken lines depict environmental structure that is included for illustrative purposes only and forms no part of the claimed design.

1 Claim, 4 Drawing Sheets
